CLAIM

The ornamental design for a charging station as shown and described.

DESCRIPTION

1. Charging station

1.1 : Front

1.2 : Back

1.3 : Left

1.4 : Right

1.5 : Top

1.6 : Bottom

1.7 : Perspective

The present design is a charging station which is used to charge self-propelled robots such as a floor sweeping machine and a lawnmower. Reproduction 1.1 is a front view of the charging station showing the new design; 1.2 is a back view thereof; 1.3 is a left view thereof; 1.4 is a right view thereof; 1.5 is a top view thereof; 1.6 is a bottom view thereof; and 1.7 is a perspective view thereof.

The broken lines in the reproductions illustrate portions of the charging station that form no part of the claimed design.
